GOBLET OR SIMILAR ARTICLE

Frank J. Benes, Lancaster, Ohio, assignor to Ravenscroft Ltd., Lancaster, Ohio

Term of patent 14 years

Filed May 6, 1970, Ser. No. 22,835

Int. Cl. D7—01

U.S. Cl. D36—8

FIG. 1.

FIG. 3.

FIG. 1 is an elevational view of a goblet or similar article showing my new design in the size and proportions of a water glass;

FIG. 2 is a top plan view thereof;

FIG. 3 is an elevational view of a goblet or similar article showing my new design in the size and proportions of a juice glass; and

FIG. 4 is an elevational view of a goblet or similar article showing my new design in the size and proportions of a parfait glass.

I claim:

The ornamental design for a goblet or similar article, substantially as shown and described.
